UNITED STATES PATENT OFFICE.

JAMES TARBOTTON ARMSTRONG AND AXEL ORLING, OF LONDON,
ENGLAND.

ELECTROCAPILLARY APPARATUS.

No. 798,482.

Specification of Letters Patent.

Patented Aug. 29, 1905.

Application filed February 2, 1904. Serial No. 191,875.

To all whom it may concern:

Be it known that we, JAMES TARBOTTON ARMSTRONG, a subject of the King of England, and AXEL ORLING, a subject of the King of Sweden and Norway, both residing at London, England, have invented new and useful Improvements in Electrocapillary Apparatus, of which the following is a specification.

Our invention relates to apparatus employed to detect the presence of electrical currents, and has for its object improvements whereby extremely weak currents may be detected and caused to actuate other apparatus or mechanism directly or through one or more relays.

In carrying out our invention we make use of the electrocapillary force exerted at the surfaces in contact of certain dissimilar fluid conductors (such as mercury and dilute acid or a solution of spirits of wine and potassium iodid) when an electric current flows through one to the other. This force we employ to disturb the balance existing between the hydrostatic pressure of a column of one of the fluid conductors and a capillary force which normally supports such column, whereby the said column may be raised or caused to flow and a relay-circuit may be closed.

The normal condition of the apparatus is one of equipoise, and the effect of the electrocapillary force is to disturb the equilibrium. It is therefore manifest that the displacement (which always accompanies the passage of even the weakest currents) must cause a preponderance on one side that will effectually operate the apparatus.

According to our invention the fluid conductors are contained by separate receptacles which communicate with each other through a tube or other suitable channel, as is herein-after particularly described with reference to the accompanying drawings, in which—

Figure 1 shows our invention in vertical section diagrammatically, and Fig. 2 illustrates a modification thereof hereinafter referred to.

According to our invention we employ a chamber *c*, containing mercury *e* and provided with a tubular leg *f^x*, which is constricted at its end *h^x*, so as to normally resist the flow of mercury from the said chamber. The leg *f^x* dips into the funnel-shaped leg of a siphon *b^x*, whose lower extremity is closed but for a central perforation *b^z*. The short leg of the siphon *b^x* dips into the chamber *b*, that con-

tains dilute acid or other suitable liquid *d*, from which the long leg is kept supplied, while its escape through the annular space between its lower extremity and that of the leg *f^x* is prevented by the surface tension of the dilute acid. Sufficient of the dilute acid, however, is drawn by capillary attraction into the constricted end *h^x* of the leg *f^x*, through which electric connection with the mercury is established. Upon the passage of a current from mercury to dilute acid displacement takes place in the same direction, resulting in a flow of the mercury from the leg *f^x*, which thereafter falls through the perforation *b^z*, which may be slightly larger than the constricted end of the said leg *f^x*. This mercury during its further descent is caused to bridge a "break" *n^x* in the relay-circuit *p*, and so close it. Instead of the terminals of the relay-circuit being arranged as shown in Fig. 1 they may be interleaved, as shown in Fig. 2. The mercury that is thus delivered falls into a reservoir *f'^x*, in which is located a float *f^z*, provided with an upwardly-extending member *f^o*, that is pivoted to a suitably-fulcrumed lever *f⁷*, to whose opposite extremity is connected a displacer *f⁸*, located in chamber *c*. As the mercury flows into the reservoir *f'^x* the float *f^z* is raised, and the displacer *f⁸* is lowered so that the level of the mercury *e* in the chamber *c* is maintained.

It is obvious that we may employ two or more capillary elements in order that a larger quantity of mercury may be delivered or displaced when a current passes through the apparatus.

What we claim as our invention, and desire to secure by Letters Patent, is—

1. In electrocapillary apparatus, the combination of two contiguous tubes, containing different fluids, means for sending an electric current through them or a part thereof to cause a change in their electrocapillary condition, permitting one of them to fall from its tube, and an electric circuit provided with contacts arranged to be connected electrically by the fluid thus falling substantially as set forth.

2. In electrocapillary apparatus, the combination of two contiguous tubes containing different fluids with means for sending an electric current through them or a part thereof to cause a change in the electrocapillary condition of the said liquids, permitting one of

them to fall from its tube, an electric circuit provided with contacts arranged to be connected electrically by the fluid thus falling, a reservoir supplying the latter fluid and means 5 governed by the falling fluid for causing the level of the fluid in said reservoir to be maintained substantially as set forth.

3. In electrocapillary apparatus, the combination of two concentric tubes containing 10 different fluids in contact at the point of discharge, with means for sending an electric current through the same to effect a change in their electrocapillary condition and permitting one of the said fluids to fall, a reservoir 15 supplying the latter fluid and means, put into operation by the fall thereof, for maintaining the level of the fluid in the said reservoir substantially as set forth.

4. In electrocapillary apparatus, the combination of two bodies of different fluids in 20 contact at the point of discharge, means for containing and supporting them, means for sending an electric current through them or a part thereof to effect a change in their electrocapillary condition and permitting one of the said fluids to fall and means, governed by the fall of the said fluid, for maintaining unchanged its level in the said reservoir substantially as set forth.

30 5. In electrocapillary apparatus, a reservoir for mercury in combination with a fluid-conducting tube having a constricted end leading from said reservoir, a receptacle for dilute acid or other suitable liquid receiving the constricted end of the fluid-conducting tube, means of directing an electric current through said fluids or a part thereof to produce a flow of fluid, relay-contacts adapted to be electrically connected by the flowing or falling fluid, 35 a vessel to receive the fallen fluid, a displacer located in the mercury-reservoir and means actuated by said fallen fluid for operating said displacer and to thereby cause the level of the mercury in the reservoir to be maintained substantially as and for the purpose set forth.

6. In electrocapillary apparatus, a reservoir for mercury in combination with a fluid-conducting tube having a constricted end leading from said reservoir, a receptacle for dilute acid 40 or other suitable liquid receiving the constricted end of the fluid-conducting tube, means of conducting an electric current through said fluids or a part thereof to produce a flow of fluid, relay-contacts adapted to be electrically connected by the flowing or falling fluid, a vessel to receive the fallen fluid, a float located therein, a lever actuated by said float and a displacer located in the mercury-reservoir and adapted to be depressed by said lever so as to 45 maintain the level of the mercury therein substantially as and for the purpose set forth.

60 7. In electrocapillary apparatus, a reservoir for mercury in combination with a fluid-conducting tube having a constricted end leading

from said reservoir, a receptacle for dilute acid 65 or other suitable liquid, a second fluid-conducting tube leading therefrom and into which the first fluid-conducting tube extends and is so arranged that their respective delivery ends are concentric and of capillary proportions, means 70 of directing an electric current through said fluids or a part thereof to produce a flow of fluid, relay-contacts adapted to be electrically connected by the flowing or falling fluid, a vessel to receive the fallen fluid a displacer located 75 in the mercury-reservoir and means actuated by the fallen fluid for operating said displacer and to thereby cause the level of the mercury in the reservoir to be maintained substantially as and for the purpose set forth. 80

8. In electrocapillary apparatus, a reservoir for mercury in combination with a fluid-conducting tube having a constricted end leading from said reservoir, a receptacle for dilute acid or other suitable liquid, a second fluid-conducting tube of siphon form leading therefrom and into which the first fluid-conducting tube extends and is so arranged that their respective delivery ends are concentric and of capillary proportions, means of directing an electric current 85 through said fluids or a part thereof to produce a flow of fluid, relay-contacts adapted to be electrically connected by the flowing or falling fluid a vessel to receive the fallen fluid, a displacer located in the mercury-reservoir, 90 and means actuated by the fallen fluid for operating said displacer and to thereby cause the level of the mercury in the reservoir to be maintained substantially as and for the purpose set forth. 95

10. In electrocapillary apparatus, the combination of acid-receptacle *b* and a siphon-tube *b* extending therefrom with a mercury-tube *c* extending down through the long leg of said siphon-tube and permitting the two liquids to 105 be in contact at its discharge end, a mercury-reservoir *c* supplying the tube *c*, relay-contacts arranged under the latter tube in position to be bridged by the fall of the mercury from the said tube, means for sending an electric current through the liquids in the said receptacle, reservoir and tubes, a receptacle *f* for the discharged mercury, a float *f* therein, a displacer *f* in the reservoir *c* and mechanism connecting said float with said displacer in order 110 that the accumulation of discharged mercury may lower the said displacer and maintain unchanged the level of mercury in the reservoir *c* substantially as set forth. 115

In testimony whereof we have signed our 120 names to this specification in the presence of two subscribing witnesses.

JAMES TARBOTTON ARMSTRONG,
AXEL ORLING.

Witnesses:

W. H. WOOD,
E. A. GODDIN.

It is hereby certified that in Letters Patent No. 798,482, granted August 29, 1905, upon the application of James Tarbotton Armstrong and Axel Orling of London, England, for an improvement in "Electrocapiillary Apparatus," an error appears in the printed specification requiring correction, as follows: In the heading the words and figures "Application filed February 2, 1904," should read *Original application filed May 19, 1902. Serial No. 108,139. Divided and this application filed February 2, 1904;* and that the said Letters Patent should be read with this correction therein that the same may conform to the record of the case in the Patent Office.

Signed and sealed this 7th day of November, A. D., 1905.

[SEAL.]

F. I. ALLEN,
Commissioner of Patents.
